CLAIM

The ornamental design for a mailing pouch, as shown and described.

DESCRIPTION

FIG. 1 is a perspective view of the mailing pouch showing my new design;

FIG. 2 is a front view thereof;

FIG. 3 is a rear view thereof;

FIG. 4 is a right side view thereof;

FIG. 5 is a left side view thereof;

FIG. 6 is a bottom view thereof;

FIG. 7 is a top view thereof; and,

FIG. 8 is a rear perspective view thereof.

The broken line showing of portions of the mailing pouch is included for the purpose of illustrating environment structure and forms no part of the claimed design.
